HENRY BRINER AND EMIL BRINER, OF MANHATTANVILLE, NEW YORK.

Letters Patent No. 79,631, dated July 7, 1868.

IMPROVEMENT IN STEEL SHANKS FOR BOOTS AND SHOES.

The Schedule referred to in these Letters Patent and making part of the same.

TO ALL WHOM IT MAY CONCERN:

Be it known that we, HENRY BRINER and EMIL BRINER, of Manhattanville, in the county and State of New York, have invented a new and useful Improvement in Steel Shanks for Boots and Shoes; and we do hereby declare that the following is a full, clear, and exact description thereof, which will enable those skilled in the art to make and use the same, reference being had to the accompanying drawings, forming part of this specification.

This invention relates to an improvement in the strips of spring-steel or other spring-metal called "steel shanks," for stiffening the bottoms of boots and shoes under the hollow of the foot, or for supporting and keeping in place that portion of the leather bottoms of boots and shoes.

And the invention and improvement consist in tipping or capping such steel shanks with some metal or material which shall not spring with the steel, but accommodate itself to the form of the pieces of leather between which it is confined.

Figure 1 is a side view of an ordinary full-sized steel shank, with our improved tip or cap attached.

Figure 2 is an edge view of the same.

Similar letters of reference indicate corresponding parts.

A is the steel shank in ordinary use.

These shanks are made of sheet steel, so cut as to fit right and left-hand boots and shoes, (or in pairs,) fig. 1 being for a right boot, as indicated by its shape.

They are curved or bowed upward, so as to correspond to the shape of the hollow of the foot, or to that part of the bottom of the boot, as indicated in fig. 2.

The end marked B is fastened securely in the heel of the boot or shoe, the other end being left loose between the layers of leather, so as to allow of its springing more or less when the wearer is walking. The forward end being thus left loose, and suffered to work or move at every step, it receives from the springing of the steel a vertical motion, which penetrates and eventually wears through the leather, thus ruining the boot or shoe.

This very objectionable and damaging motion is unavoidable when the steel shank is in one piece.

To remedy the difficulty is the object of our invention.

For this purpose we attach a piece or cap of tin or copper, or any other suitable metal or material, to the forward end of the shank, which shall not be elastic, so as to be controlled by the spring of the steel, but which shall adapt itself to the layers of leather, and be subjected by the spring of the steel to a slight longitudinal motion only, and without any tendency to wear through the leather.

C is the cap or tip, which is simply a piece of metal, doubled and slipped on to the end of the steel, and riveted thereto, as seen at d, or attached or connected to or with the steel in any suitable manner.

It will be seen that this cap C projects outward or forward of the steel, and, not being elastic, it will accommodate itself to the leather without vertical motion.

We do not confine ourselves to any particular form or size for the cap C.

We claim as new, and desire to secure by Letters Patent—

As an improved article of manufacture, the steel shank for boots and shoes, when its free end is provided with an inelastic cap, C, for the purpose of preventing injury to the sole of the boot or shoe by the longitudinal motion produced by the action of the spring, as herein shown and described.

The above specification of our invention signed by us, this 16th day of April, 1868.

EMIL BRINER,
HENRY BRINER.
